US00D831976S

(12) **United States Design Patent** (10) **Patent No.:** **US D831,976 S**
Nicoline (45) **Date of Patent:** **** Oct. 30, 2018**

(54) **MAKEUP BRUSH**

(71) Applicant: **Paris Presents Incorporated**, Gurnee, IL (US)

(72) Inventor: **Alyssa C. Nicoline**, McHenry, IL (US)

(73) Assignee: **PARIS PRESENTS INCORPORATED**, Gurnee, IL (US)

(**) Term: **15 Years**

(21) Appl. No.: **29/618,156**

(22) Filed: **Sep. 19, 2017**

(51) LOC (11) Cl. **04-02**

(52) U.S. Cl.

USPC **D4/199**; D4/138

(58) **Field of Classification Search**

USPC D4/114, 115, 116, 117, 118, 119, 120, D4/121, 122, 123, 124, 125, 126, 127, D4/128, 129, 130, 131, 132, 133, 134, D4/135, 136, 137, 138, 199; D28/7, 20, D28/25, 28, 30

(57) **CLAIM**

The ornamental design for a makeup brush, as shown and described.

DESCRIPTION

FIG. 1 is a perspective view of a front, top, and right side of an ornamental design for a makeup brush;

FIG. 2 is a front elevational view of the makeup brush of FIG. 1;

FIG. 3 is a rear elevational view of the makeup brush of FIG. 1;

FIG. 4 is a right side elevational view of the makeup brush of FIG. 1;

FIG. 5 is a left side elevational view of the makeup brush of FIG. 1;

FIG. 6 is a top plan view of the makeup brush of FIG. 1; and, FIG. 7 is a bottom plan view of the makeup brush of FIG. 1.

The dash-dash-dash-dash lines are for the purpose of illustrating environmental structure and form no part of the claimed design. The dash-dot-dash lines form no part of the claimed design and represent a boundary line.

1 Claim, 3 Drawing Sheets
